US00D986997S

(12) **United States Design Patent** (10) **Patent No.:** **US D986,997 S**
Andrews (45) **Date of Patent:** **** May 23, 2023**

(54) **GOLF CLUB HEAD**(71) Applicant: **PARSONS XTREME GOLF, LLC**,
Scottsdale, AZ (US)(72) Inventor: **Matthew T. Andrews**, Scottsdale, AZ
(US)(73) Assignee: **PARSONS XTREME GOLF, LLC**,
Scottsdale, AZ (US)(***) Term: **15 Years**(21) Appl. No.: **29/799,457**(22) Filed: **Jul. 14, 2021****Related U.S. Application Data**

(60) Division of application No. 29/714,587, filed on Nov. 25, 2019, now Pat. No. Des. 927,619, which is a continuation-in-part of application No. 29/702,704, filed on Aug. 21, 2019, now abandoned.

(51) **LOC (14) Cl.** ..... **21-02**(52) **U.S. Cl.**USPC ..... **D21/736**(58) **Field of Classification Search**USPC D21/736-746, 759

(Continued)*Primary Examiner* — Mitchell I. Siegel(57) **CLAIM**

The ornamental design for a golf club head, as shown and described.

DESCRIPTIONFIG. 1 is a top perspective view of a golf club head;
FIG. 2 is a bottom perspective view of the golf club head of FIG. 1;

FIG. 3 is a front elevational view of the golf club head of FIG. 1;

FIG. 4 is a rear elevational view of the golf club head of FIG. 1;

FIG. 5 is a top view of the golf club head of FIG. 1;
FIG. 6 is a bottom view of the golf club head of FIG. 1;
FIG. 7 is a left side view of the golf club head of FIG. 1; and,
FIG. 8 is a right side view of the golf club head of FIG. 1.
The broken lines shown on the drawings form no part of the claimed design.**1 Claim, 4 Drawing Sheets**| (56)	References Cited
